(57) **CLAIM**

The ornamental design for an astronomical clock displaying moon phase, as shown and described.

DESCRIPTION

The patent or application file contains at least one drawing executed in color. Copies of the patent or patent application publication with color drawing(s) will be provided by the Office upon request and payment of the necessary fee.

FIG. 1 is a front view of an astronomical clock according to a first embodiment of our new design, including a displayed full moon phase;

FIG. 2 is the front view thereof, including a displayed half moon phase;

FIG. 3 is the front view thereof, including a displayed half moon phase;

FIG. 4 is the front view thereof, including a displayed quarter moon phase;

FIG. 149 is the front view thereof, including a displayed three quarter moon phase;

FIG. 150 is the front view thereof, including a displayed new moon phase;

FIG. 151 is a front perspective view thereof;

FIG. 152 is a bottom view thereof;

FIG. 153 is a left side elevational view thereof, the right side elevational view being a mirror image;

FIG. 154 is a front view of an eighteenth embodiment of the astronomical clock, including a displayed full moon phase;

FIG. 155 is the front view thereof, including a displayed half moon phase;

FIG. 156 is the front view thereof, including a displayed half moon phase;

FIG. 157 is the front view thereof, including a displayed quarter moon phase;

FIG. 158 is the front view thereof, including a displayed three quarter moon phase;

FIG. 159 is the front view thereof, including a displayed new moon phase;

FIG. 160 is a front perspective view thereof;

FIG. 161 is a bottom view thereof; and,

FIG. 162 is a left side elevational view thereof, the right side elevational view being a mirror image.
